DESIGN.

—
O. HEINIGKE.

CARPET.

No. 15,459.

Patented Oct. 14, 1884.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 15,459, dated October 14, 1884.

Application filed August 6, 1884. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists of five closely-massed groups upon a ground resembling lace border-work. The small figure-work resembling lace-work, which forms the ground, appears in the interstices between the flower groups, and is arranged in right lines, producing a general effect resembling paneling.

The group A is in the center of the photograph. It consists of a large leaf mass with occasional flowers. On the right is a scattered leaf cluster. Below, on the right, is a group of star-shaped flowers and projecting leaf-sprays, and a similar group on the left. Above, on the left, is a large flower on a leaf mass, and having projecting leaf and lichen sprays. On the right above is a drooping spray of blossoms.

The group B is shown at the upper and lower edges of the photograph. It consists of a large flower and leaf mass, fern-sprays above on the left, a large rose and leaves above on the right, and an open flower having Greek crosses directly above it. Below the group are several small leaf and blossom sprays.

The group C is shown at the right lower and

left upper corners of the photograph. There is a large star-shaped flower and large leaves at its center. Above, on the right, is a cluster of small star-shaped flowers. On the left are sprays of grape-leaves and tendrils.

The group D is shown at the left center of the photograph and at the right above. A leaf mass lies below a single star-shaped flower. On the right above is a blossom cluster. Small tendril-like sprays project on all sides.

The group E is shown at the left of the photograph below, and at the right above, the center. Three star-shaped flowers lie on a small leaf mass. A leaf spray projects on the left below, a blossom spray on the right, and above is a small tendril-shoot.

I claim—

1. The design for a carpet, consisting of the group A, substantially as shown and described.
2. The design for a carpet, consisting of the group B, substantially as shown and described.
3. The design for a carpet, consisting of the group C, substantially as shown and described.
4. The design for a carpet, consisting of the group D, substantially as shown and described.
5. The design for a carpet, consisting of the group E, substantially as shown and described.
6. The design for a carpet, consisting of the groups A, B, C, D, and E, substantially as shown and described.
7. The design for a carpet, consisting of the groups A, B, C, D, and E, and the paneled lace-work ground, substantially as shown and described.

OTTO HEINIGKE.
